UNITED STATES PATENT OFFICE.

LAMBERT J. BORDO, OF PHILADELPHIA, PENNSYLVANIA.

FLUID-PRESSURE VALVE.

988,689.

Specification of Letters Patent.

Patented Apr. 4, 1911.

Application filed August 9, 1907. Serial No. 387,758.

To all whom it may concern:

Be it known that I, LAMBERT J. BORDO, a citizen of the United States of America, residing in the city and county of Philadelphia, in the State of Pennsylvania, have invented a certain new and useful Improvement in Fluid-Pressure Valves, of which the following is a true and exact description, reference being had to the accompanying 10 drawings, which form a part thereof.

The present invention relates to fluid pressure valves, and particularly to that type of such valves in which the valve member is moved in one direction from a neutral position under one operative condition and in the opposite direction from a neutral position under another operative condition.

The object of the present invention is the production of a simple and effective construction in which a valve of the type just described is combined with means automatically tending to hold the valve in a neutral position and return it to that position when it has been moved in either direction from such neutral position.

The various features of novelty which characterize my invention are pointed out with particularity in the claims annexed to and forming a part of this specification. 30 For a better understanding of my invention, however, reference may be had to the accompanying drawings and descriptive matter in which I have illustrated and described one of the forms in which my invention may be embodied.

Of the drawings, Figure 1 is a sectional plan on the line 1-1 of Fig. 2. Fig. 2 is a sectional elevation on the line 2-2 of Fig. 1, and Fig. 3 is an exploded perspective view showing parts of the valve return mechanism.

In the drawings, A represents the valve casing proper, which is provided with a conical bearing A' for the conical rotary 45 valve B, and with four ports A², A³, A⁴, and A⁵. The valve B is provided with two arc shaped ports B' and B². An operating handle C is secured to the upper end of the valve B. When the valve handle is in the 50 position shown in full lines in Fig. 1, the various ports in the valve casing and valve are all closed, but when the valve handle is moved clockwise into the lower dotted line position of Fig. 1, the valve casing 55 ports A² and A⁴ are connected through port B', and casing valves A³ and A⁵ are connected through valve port B². Simi-

larly, when the handle is moved counterclockwise into the other dotted line position shown in Fig. 1, ports A² and A³ are connected by port B', and ports A⁴ and A⁵ are connected through port B². The particular valve disclosed is used for the operation of compressed air or hydraulic hoists or the like, and the ports A³ and A⁴ are the outlet ports of the valve casing connected to the opposite ends of the cylinder of the fluid pressure device control; while port A² is the inlet port leading from the source of compressed air or other fluid under pressure, and port A⁵ is an exhaust port.

To the underside of the valve casing A is secured a supplemental casing in which the valve return mechanism is mounted. 75 The supplemental casing comprises a cup-shaped member D, and a cover member D'. The valve casing A, cover member D', and cup member D are connected together as by means of the bolts D².

The return mechanism comprises a rotatable member E in alignment with the valve B. The upper end of the member E passes through an aperture formed for the purpose in the cover member D', and is provided with a tongue E' which enters the socket B² formed in the base end of the conical valve B. By this arrangement, relative angular movement between the members E and B is prevented, while at the same time 90 the valve B is free to move toward and from the member E to permit the valve to properly seat itself in its bearing, as under the action of fluid pressure admitted to the chamber formed between the lower end of 95 the valve casing A and the cover or diaphragm member D' through the port A⁶ leading from the inlet passage A² of the valve.

The mechanism for normally holding the 100 member E in the position in which the valve is held in the full line position shown in Fig. 1, and for urging the member E back to this position when moved out of it in either direction, is all within the supplemental casing. This mechanism comprises a collar F surrounding the member E just below the cover member D'. The collar is provided at its upper surface with a flange F' provided with a series of grooves F², in 110 which a key F³ may be inserted. The inner end of the key F³ is adapted to engage a lug E² formed on the member E, and the outer end of the key is adapted to engage a

lug D³ formed on the under side of the cover member D'. The under side of the collar F is provided with a series of guide lugs F⁴ for the helical spring H which surrounds the member E and extends between the collar F, and a somewhat similar collar G surrounding the lower end of the member E. One end of the helical spring H is hooked on to one of the lugs F⁴, and the other end of the spring is hooked on to one of a corresponding set of lugs G' formed on the collar G. The collar G is provided with an upper lug G³ adapted to engage the lug E² on the member E, and on its lower side with a lug G² adapted to engage a lug D⁴ on the bottom wall of the casing member D. It will be observed that the lugs E² and E³ on the member E so engage the collars F and G through key F³ and lug G³ respectively, and that the collars so engage the casing through key F³ and lug D³ and lug G² and lug D⁴, that when the member E is moved counter-clockwise from its normal position the collar G is held stationary and the collar F is rotated with the member E, and that when the member E is rotated in the opposite direction from the normal position the collar F is held stationary and the collar G is rotated. In consequence, a movement of the member E in either direction out of the normal position tends to increase the tension on the spring H, which at all times urges the member E toward its normal position. The tension of the spring may be adjusted by inserting the key F³ in different notches F². In the construction shown and described, the valve casing and the supplemental casing and return mechanism mounted in it are separate structures, each of which may be made and assembled by itself, but these structures are so arranged that they may be readily and easily connected together in order to form a complete and highly efficient mechanism. The provision of the spring return mechanism with a valve of the type disclosed is a marked utility, particularly where, as is frequently the case, a number of controlling valves for different hoists are controlled by a single operator. In such cases, loss of compressed air or other working fluid occurring when the operator leaves one valve open longer than is necessary because his attention is directed to other controlling valves, is not uncommon.

Having now described my invention, what I claim as new and desire to secure by Letters Patent, is:

1. In combination, a valve casing having a bearing for a rotary valve, and a plurality of valve controlled ports, a valve mounted in said bearing and provided with ports, said valve being rotatable in both directions

from a neutral position to bring different sets of ports into register, a rotatable member, a coupling between said member and the valve, a spring return for said rotatable member normally tending at all times to move the member into the position corresponding to the neutral position of the valve, and a supplemental casing detachably secured to the valve casing, said member being journaled in, and it and the spring return being inclosed by, said supplemental casing.

2. In combination, a valve casing having a bearing for a rotary valve, and a plurality of valve controlled ports, a valve mounted in said bearing and provided with ports, said valve being rotatable in both directions from a neutral position to bring different sets of ports into register, a rotatable member, a coupling between said member and the valve, a spring return for said rotatable member normally tending at all times to move the member into the position corresponding to the neutral position of the valve, said coupling permitting movement of the valve toward and away from said member, and a supplemental casing detachably secured to the valve casing, said member being journaled in, and it and the spring return being inclosed by, said supplemental casing.

3. In combination, a valve casing having the conical bearing A', and the inlet port A² and the outlet ports A³ and A⁴ on opposite sides of the inlet port, the conical valve member B mounted in said bearing A', and having the ports B' and B² arranged to connect the inlet port A² with one or the other of the outlet ports A³ and A⁴ when the valve is turned in one direction or the other from a neutral position, said casing and valve being arranged so that the fluid pressure of the inlet port acts on the large end of the conical valve member to hold it forcibly in said bearing, a supplemental casing detachably secured to the valve casing, a return member E mounted in said supplemental casing, said return and valve members being provided one with a socket and the other with a tongue entering said socket, whereby the valve member B is free to move toward and away from the return member E, but angular relative movement between the members is prevented, and resilient means acting on said return member and tending at all times to urge it toward the position corresponding to the neutral position of the valve.

LAMBERT J. BORDO.
